UNITED STATES PATENT OFFICE.

HORACE RESLEY, OF CUMBERLAND, MARYLAND.

BOTTLE-STOPPER FASTENING.

SPECIFICATION forming part of Letters Patent No. 273,159, dated February 27, 1883.

Application filed October 30, 1882. (Model.)

To all whom it may concern:

Be it known that I, HORACE RESLEY, of Cumberland, in the county of Allegheny and State of Maryland, have invented certain new and useful Improvements in Bottle-Stopper Fastenings; and I do hereby declare the following to be a full, clear, and exact description of the invention, such as will enable others skilled in the art to which it pertains to make and use it, reference being had to the accompanying drawings, which form part of this specification.

My invention relates to an improvement in bottle-stopper fastenings; and it consists in an operating-lever having its lower ends formed into stops, which catch against the sides of the wire to which the stopper is attached, so that when the lever is forced downward against the side of the bottle the stopper will be first raised upward from the neck of the bottle, and then forced over upon the same side of the bottle as the operating-lever, as will be more fully described hereinafter.

The object of my invention is to provide a bottle-stopper fastening in which the operating-lever is made to close upward over the top of the stopper, and which is adapted for use upon bottles having different lengths of neck, and which is so connected to the wire upon which the stopper is pivoted that the stopper is always thrown over upon the same side of the bottle as the lever, whereby, after the stopper has been opened, the very act of moving the stopper back into place will force the lever up, ready to lock the stopper.

Figure 1 is a side elevation of the bottle, showing the stopper fastened in place. Fig. 2 is a similar view, showing the stopper open. Fig. 3 is a view showing the stopper fastened in place, taken at right angles with Figs. 1 and 2. Fig. 4 is an enlarged detail view. Fig. 5 is a perspective of my invention.

A represents a bottle of any desired shape, size, or construction, and which has the enlargement B upon the upper end of its neck. Applied to this neck just below the enlargement is the wire C, which extends a little over half-way around the neck, and which has its two ends bent downward and outward, so as to form the pivotal points D, upon which the operating-lever E is pivoted. This wire C is held in place upon the neck of the

bottle by a similar wire, F, in the usual manner. This operating-lever has the loop G formed at the center of its top and two side loops, H, near its lower ends, so as to catch over the pivots, and the loops I, formed at its extreme lower ends, through which the lower ends of the wire J are made to pass. The operating-lever has the circle or loop G formed at its top, so that by enlarging or contracting the circle a variable pressure upon the stopper can be obtained. This loop is necessary, as the top of the bottle-neck very often varies in length, and the loop G allows the wire E to expand in proportion as the upward pressure causes the loop to contract. From this loop G the lever is curved downward and outward, as shown in Fig. 3, so as to give the lever a suitable amount of elasticity. The extreme lower ends of the lever, after forming the loops through which the ends of the stopper-wire are passed, are turned upward so as to form the stops O for catching against the sides of the stopper-wire, and thus prevent it from moving when the stopper is opened upon the opposite side of the bottle from the operating-lever. These stops are so made that they allow the lever and the stopper-wire to extend almost at right angles to each other, but no farther. By this construction, when the lever is forced downward against the side of the bottle, the stopper is first raised upward from the neck of the bottle and then thrown over upon the same side of the bottle as the lever. When the stopper is raised into position to again close the bottle this wire strikes against the stops and raises the operating-lever upward, so that it is in position to be forced upon the top of the stopper, and thus lock the stopper in position.

Upon the top of the stopper, which will be made of any suitable metal, will be formed the ridge or stop P, over which the loop G is forced. As soon as the loop passes over this ridge or stop the elasticity of the wire out of which the lever is made causes the loop to snap down behind the stop, so as to lock the lever in place. The stopper itself will be preferably formed of rubber, which will be secured to the metallic plate in any suitable manner.

Having thus described my invention, I claim—

1. In a bottle-stopper fastening, the combi-

nation of the wire which is attached to the stopper and the operating-lever pivoted upon a suitable support, the lower ends of the lever being formed into stops, so as to force the stopper over upon the same side of the bottle as the lever, substantially as shown.

2. In a bottle-stopper fastener, the combination of the wire J, having the stopper attached to it, with the wire E having the loop G and

the stop O formed as a part thereof, and the neck-band pivot, substantially as described.

In testimony whereof I affix my signature in presence of two witnesses.

HORACE RESLEY.
